(57) **CLAIM**

The ornamental design for a head for a golf club as shown and described.

DESCRIPTION

FIG. 1 is a perspective view of a head for a golf club showing first embodiment of my new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a perspective view of a head for a golf club showing second embodiment of my new design;

FIG. 8 is a front view thereof;

FIG. 9 is a left side view thereof;

FIG. 10 is a top view thereof; and,

FIG. 11 is a bottom view thereof.

The broken lines depict portions of the head for a golf club in which the design is embodied that are not considered part of the claimed design.

The dot-dash lines show a boundary between the claimed design and unclaimed portions.
